DESIGN FOR A WHEEL BALANCING MACHINE

Frank L. Haasl and Charles F. Kiser,
Chicago, Ill.

Application November 27, 1939, Serial No. 88,500

Term of patent 7 years

To all whom it may concern:

Be it known that we, Frank L. Haasl and Charles F. Kiser, citizens of the United States and residents of Chicago, Illinois, have invented a new, original, and ornamental Design for a Wheel Balancing Machine, of which the following is a specification, reference being had to the accompanying drawings, forming part thereof.

Fig. 1 is a perspective view showing the front, right and top of the machine.

Fig. 2 is a top plan view.

Fig. 3 is a side elevation of the left side of the machine.

Fig. 4 is a side elevation of the right side of the machine on a reduced scale.

What we claim is:

The ornamental design for a wheel balancing machine, as shown.

FRANK L. HAASL.
CHARLES F. KISER.
